US0D1028625S

(12) United States Design Patent (10) Patent No.: US D1,028,625 S
(45) Date of Patent:  May 28, 2024

(54) BEVERAGE BOTTLE

(71) Applicant: Bluewater Innovations AB, Stockholm (SE)

(72) Inventors: Bengt Rittri, Stockholm (SE); Magnus Lundström, New York, NY (US)

() Term: 15 Years

(21) Appl. No.: 35/517,749

(22) Filed: Jul. 8, 2022

(80) Hague Agreement Data

Int. Filing Date: Jul. 8, 2022

Int. Reg. No.: DM/222057

Int. Reg. Date: Jul. 8, 2022

Int. Reg. Pub. Date: Jul. 14, 2023

(30) Foreign Application Priority Data

Jan. 27, 2022 (EM) 008842082-0001

(51) LOC (14) Cl. 07-01

(52) U.S. Cl.

USPC D7/523; D7/511; D9/504
